E. KOGLER.

GEAR CASE.

APPLICATION FILED NOV. 14, 1921.

1,409,302.

Patented Mar. 14, 1922.

UNITED STATES PATENT OFFICE.

EDUARD KOGLER, OF JERSEY CITY, NEW JERSEY, ASSIGNOR TO CHILLINGWORTH MANUFACTURING COMPANY, OF JERSEY CITY, NEW JERSEY, A CORPORATION OF NEW JERSEY.

GEAR CASE.

1,409,302.

Specification of Letters Patent. Patented Mar. 14, 1922.

Application filed November 14, 1921. Serial No. 514,866.

To all whom it may concern:

Be it known that I, EDUARD KOGLER, a citizen of Germany, (who has declared his intention to become a citizen of the United States,) and resident of Jersey City, in the county of Hudson and State of New Jersey, have invented certain new and useful Improvements in Gear Cases, of which the following is a specification.

10 This invention relates to gear cases for motor vehicles, having especial reference to end-suspended gear cases for electric motor trucks.

15 The object of my invention is to provide a simple and relatively inexpensive gear case which possesses adequate strength and lightness, and which embodies reliable end suspension devices which are so constructed and arranged as to reinforce the structure 20 and effectually counteract the severe lateral and torsional strains to which the case is subjected, thereby insuring the rigidity and increasing the durability and general efficiency of the structure.

25 In the preferred embodiment of my invention herein illustrated the body of the gear case comprises two complementary trough-shaped sections of oval form in cross-section, each section being an integral sheet 30 metal structure. The ends of the respective sections have affixed thereto substantial brackets of special construction which not only effectually reinforce the case but also provide rigid end supporting jaws which 35 are reliably yet detachably coupled, as will be hereinafter fully set forth. The precise scope of the invention will be defined in the appended claims.

In the drawings—

40 Figure 1 is a front elevation of my improved gear case, the supporting arms therefor being shown in section.

Fig. 2 is a plan of the gear case.

Fig. 3 is an end elevation of the structure.

45 Referring to the drawings, 5, 5 designate two trough-shaped sections, each of which comprises an integral sheet metal structure. The two bodies, of which one is the counterpart of the other, are fitted together edge 50 to edge to provide a shallow casing of suitable size and form to contain the intermeshing gears of the power transmitting mechanism for the vehicle to which the case is ap-

plied. The casing thus provided is preferably of oval form in longitudinal section. 55 The longitudinal edges of the two sections are provided with corresponding semi-circular recesses 6 which, when the sections are united, provide in both sides of the structure opposite circular openings for the passage of the shaft or axle carrying the driven gear wheel. The edge of the opening in that side of the case adjacent the motor, is preferably reinforced by an annulus 7 which is riveted or otherwise secured to the adjacent walls of the two sections. 60 The sections are also provided on the side adjacent the motor with corresponding semi-circular recesses 8 which afford an opening for the entrance of the motor shaft to the case, 70 which shaft carries the driving gear wheel.

The side walls of one of the sections, in the present instance the upper section, has affixed thereto, by rivets or welding, longitudinally disposed strips 9 which provide 75 flanges that overlap the adjacent edges of the other or lower section and thus prevent lateral displacement of the associated sections.

On each section, adjacent its respective 80 ends, are mounted and secured two stout brackets which project endwise from the section, each bracket being an integral casting comprising, preferably, a body 10 which is suitably shaped to rest upon the rim of the 85 section and is riveted thereto, as at 11; a lateral thrust flange 12 which overlaps the side of the section adjacent the motor and is riveted to such side, as at 13; an outwardly projecting perforated portion 14 constituting a jaw member, and lateral reinforcing ribs 15 which connect such projecting portion with the body of the bracket. The two brackets at each end of the case are suitably spaced apart so that the upper 90 and lower jaws 14 embrace the adjacent 95 and lower jaws 14 embrace the adjacent supporting arm (16) projecting from the motor case or other fixed portion of the vehicle. The jaws are rigidly secured to the respective arms by through bolts 17.

100 The construction just described provides reliable suspension devices which effectually reinforce the respective ends of the case in such a manner as to counteract the severe lateral and torsional strains to which the 105 structure is subjected at and adjacent its

points of support; and the structure as a whole combines the advantages of rigidity, strength, lightness and durability.

In the present instance suitable coupling members are applied to the jaws 14 at the respective ends of the structure, and such jaws, in conjunction with the coupling members, are secured to the respective bars by the bolts 17. Each of the coupling members illustrated comprise a yoke-like device having a body 18 with upper and lower angular end extensions 19. These extensions are perforated for the passage of the bolt 17 and the upper extension has struck up therefrom two spaced-apart lugs 21 between which the head of the bolt is seated, such lugs thus serving as a lock to prevent accidental rotation of the bolt. These lugs are also provided with perforations for the passage of a cotter pin 22, which, overhanging the head of the bolt, prevent accidental removal of the latter should the nut 23 thereof work loose.

It is to be understood that my invention is not limited to the exact details of construction herein disclosed as modifications may be made within the principle of the invention and the scope of the appended claims.

30 I claim—

1. In a gear case adapted to be suspended at its ends from spaced supports, two trough-like sections, each comprising an integral rim and sides, exterior brackets affixed to each section adjacent the respective ends of the rim, each of said brackets comprising a body mounted on the rim and having a thrust portion which laterally overlaps the section and also having a jaw which projects endwise beyond the section, and means

whereby each pair of adjacent jaws thus provided are secured to a support embraced thereby.

2. In a gear case adapted to be suspended at its ends from spaced supports, two trough-like sections, each comprising an integral rim and sides, exterior brackets affixed to each section adjacent the respective ends of the rim, each of said brackets being an integral casting comprising a body 50 mounted on the rim and having a lateral thrust flange which overlaps the adjacent side of the section, and also having an endwise projecting jaw member and lateral reinforcing ribs which connect said member with the body of the bracket, and means whereby each pair of adjacent jaws thus provided are secured to a support embraced thereby.

3. In a gear case adapted to be suspended 60 at its ends from spaced supports, two trough-like sections, each comprising an integral rim and sides, exterior brackets affixed to each section adjacent the respective ends of the rim, each of said brackets comprising a body mounted on the rim and having a thrust portion which laterally overlaps the section and also having a jaw which projects endwise beyond the section, a detachable coupling device for each pair of adjacent jaws thus provided at each end of the case, and means for securing each pair of jaws and their associated coupling device together and to a support embraced by said jaws.

Signed at Jersey City in the county of Hudson and State of New Jersey this 17th day of October, A. D. 1921.

EDUARD KOGLER.
